(57) **CLAIM**

The ornamental design for a compressor housing, as shown and described.

DESCRIPTION

FIG. 1 is a first top perspective view of a compressor housing, according to our new design, shown with an unclaimed compressor wheel;

FIG. 2 is a second top perspective view of the compressor housing shown with the unclaimed compressor wheel;

FIG. 3 is a first bottom perspective view of the compressor housing shown with the unclaimed compressor wheel;

FIG. 4 is a second bottom perspective view of the compressor housing;

FIG. 5 is a left side elevational view of the compressor housing;

FIG. 6 is a right side elevational view of the compressor housing;

FIG. 7 is a front side elevational view of the compressor housing;

FIG. 8 is a rear side elevational view of the compressor housing;

FIG. 9 is a top side view of the compressor housing shown with the unclaimed compressor wheel;

FIG. 10 is a bottom side view of the compressor housing shown with the unclaimed compressor wheel;

FIG. 11 is a top perspective view of the compressor housing shown without the unclaimed compressor wheel;

FIG. 12 is a bottom perspective view of the compressor housing shown without the unclaimed compressor wheel;

FIG. 13 is a top side view of the compressor housing shown without the unclaimed compressor wheel;

FIG. 14 is a bottom side view of the compressor housing shown without the unclaimed compressor wheel;

FIG. 15 is a top perspective view of the compressor housing shown with an unclaimed center housing rotating assembly and an unclaimed turbine housing; and,

(Continued)

FIG. 16 is a front side elevational view of the compressor housing shown with the unclaimed center housing rotating assembly and the unclaimed turbine housing. The broken lines in the figures are included for the purpose of illustrating unclaimed portions of the compressor housing and unclaimed environmental structure and form no part of the claimed design.

1 Claim, 16 Drawing Sheets
